UNITED STATES PATENT OFFICE.

SWAN F. ANDERSON, OF ROCKFORD, ILLINOIS, ASSIGNOR, BY MESNE ASSIGNMENTS,
TO PEERLESS PNEUMATIC SYSTEMS, INC., OF CHICAGO, ILLINOIS, A CORPORATION
OF ILLINOIS.

SPRAY GUN.

Application filed November 11, 1922. Serial No. 600,941.

To all whom it may concern:

Be it known that I, SWAN F. ANDERSON, a citizen of the United States, residing at Rockford, in the county of Winnebago and State of Illinois, have invented certain new and useful Improvements in Spray Guns, of which the following is a specification.

This invention pertains in general to air brushes or spray guns as they are commonly known, for spraying paints, fillers, enamels, varnishes, shellacs, dyes, stains, bronzes, aluminums, and in fact any liquid material which it is desired to spread on a surface for coating and finishing purposes.

15 The primary object of my invention is to provide a generally improved and simplified spray gun, characterized by its economy in use of both air and materials, perfect atomization and adaptability for a wide range of work, accessibility of parts requiring adjustment for different classes of work and which it is also desired to remove for cleaning and inspection, and by the simple and novel arrangement of parts which enables 20 production at a comparatively low cost.

In furtherance of the foregoing, my invention contemplates the provision of a spray gun having a body preferably in the form of a one-piece casting, having a handle and 25 a spray head portion joined by a barrel-like portion, giving a very simple, rigid and durable construction, with which the several co-operating parts may be organized in a very efficient manner. Regarding the arrangement of parts, I have aimed to provide an air and a material delivery nozzle on the spray head, a needle valve for the material-delivery means and air-supply valve for the air-delivery means in co-axial relation, and 30 a trigger for operating both valves. By arranging these valves and co-operating parts in a plane below the barrel-like portion of the body, an exceptionally simple construction is obtained, which promotes 35 economy in the cost of manufacture, enables accessibility to such parts as may require attention either for adjustment, cleaning or repair, and further provides a well-balanced spray gun capable of control to 40 a fine degree of accuracy.

Still another object of my invention is to provide an improved nozzle construction of the flat spray type characterized by the novel

manner in which the air-delivery nozzle is associated with the material-delivery nozzle. 55

Other objects and attendant advantages will be appreciated by those skilled in this art as the invention becomes better understood by reference to the following description when considered in connection with the 60 accompanying drawings, in which—

Figure 1 is a side elevation of a spray gun embodying my invention;

Fig. 2 is a vertical longitudinal sectional view through the gun; and

Figs. 3 and 4 are detail sections taken substantially on the lines 3—3 and 4—4, respectively, of Fig. 2.

Referring more particularly to the drawing, it will be observed that the body on which the several co-operating parts are mounted, is in the form of a one-piece casting, shaped to provide a handle and a spray head portion 5 and 6 respectively, connected by an intermediate barrel-like portion 7. 70 Both the handle and spray head portions depend from the intermediate portion, providing a rigid frame-work or body particularly well adapted for housing and carrying the several operating parts. 75

In the preferred construction, there is a material-supply passage 8 through the spray head 6 on a center below and parallel with the barrel-like portion 7. The liquid material to be atomized will be fed to this passage 8 through a suitable hose, not shown, but which may be attached to the threaded nipple 9, which has a passage 11 communicating with the passage 8. The material may be fed through this means by gravity, pressure, siphon, or any other means for producing the required flow. The air pressure is admitted to the body through a hose connected to a suitable source of supply and attached preferably to a threaded nipple 12 on the handle portion 5, in which is formed an air-supply passage 13 in alignment with the material-supply passage 8. 80

Upon the spray head 6, I have mounted a material-delivery nozzle and an air-delivery nozzle, designated generally by 14 and 15, respectively. The material-delivery nozzle has an end 16 threadedly engaged in the passage 8, and a body portion 17, so shaped as to be readily engaged by a wrench for tightening said nozzle in the spray head. Said

- nozzle has a central passage 18 communicating at one end with the passage 8 and terminating at its opposite end in a tapered delivery orifice 19, upon which the tapered end 5 of a needle valve 21 is adapted to seat for closing said delivery orifice. Said needle valve is adapted to be retracted by operation of a trigger 22 for opening said material-delivery orifice 19, as will be more fully described hereinafter. The exterior of said nozzle body 14 tapers toward its delivery end and terminates in a cylindrical tip 23 the peripheral wall of which is for a short distance parallel with the axis of the nozzle 15 and forms the inner wall of a central air-delivery orifice, the outer wall 24 of which is formed by the body of the air-delivery nozzle 15. This latter nozzle, it will be observed, forms a casing embracing the material-delivery nozzle 14. This casing defines the outer boundary and the nozzle 14, the inner, of an air passage 25 which communicates with the central air-delivery orifice defined by the annular walls 23 and 24. The 20 air delivery nozzle is made up of a coupling part 26 and a swivel part 27. Said coupling part is threadedly engaged on the spray head 6, concentric with the nozzle 14, and said swivel part 27 has an inner end 28 telescoping within the coupling part 27 and retained therein by an outwardly pressed or swaged flange 29. In this manner, the part 27 may be rotatably moved on the part 26, and at the same time an air-tight joint is provided between the relatively movable parts. Said swivel part has diametrically opposed air passages 31, which communicate at their inner ends with the air passage 25 and terminate at their outer ends in air-delivery orifices 32, which are adapted for delivering streams of air in converging planes for the purpose of producing in combination with the circular spray delivered through the central orifices, a fan or flat type spray. By rotative movement of the swivel part 27 on the coupling part 26, the major axis of the flat type spray may be changed from horizontal to vertical, or to any angle. 40
- 50 Air under pressure will be supplied to the passage 25, and consequently to the delivery orifice above mentioned, through an air-supply passage formed in the gun body and made up of a vertical passage 33 communicating with the air inlet passage 13, and passages 34 and 35, the former extending longitudinally through the barrel portion 7. A poppet type valve 36 urged by a compression spring 37 against a seat 38 normally closes the passage, and is adapted to be opened by rearward pressure of the trigger part 39 against the valve stem 41. A screw valve 42 regulates the flow of air through the supply passage, as will be obvious. From the foregoing, it will be evident that upon drawing the trigger 22 rearwardly by finger action, the air-supply valve will be directly opened, thereby immediately supplying air to the central and intersecting air-delivery orifices. 55
- 60 Means is provided, whereby the trigger 22 operates the material-delivery valve, at present the needle valve 21, in addition to the air-supply valve 36. The needle valve will be opened subsequently to opening the air-supply valve, the point of opening being regulated by an adjustment so that the interval between the opening of both valves may be varied to suit the requirements, and if desired, both valves may be caused to open simultaneously. To this end a lost motion connection is provided between the trigger 22 and the needle valve 21, including an adjustment, whereby the lost motion may be varied from zero to the maximum. It will be noted that the needle valve passes through a stuffing box 43 in the inner end of the passage 18, and is threadedly engaged in its inner end 44 in a sleeve 45 slidable axially in a lug 46 depending from the body portion 7, said stuffing box may be suitably constructed and is preferably shaped to receive a packing disposed around the needle valve and includes a threaded member, in this instance a packing gland having a knurled part 40 adapted to be turned by the fingers for compressing the packing to prevent leakage of the material around or passing from the passage 8. A cross head 47 fixed to the sleeve 45, has reduced ends 48 slidable in slots 49 in a yoke 51, which straddles the lug 46 and is pivotally attached by means of a pin 52 to the trigger 22. This trigger, it will be observed, has sides 53 straddling the body portion 7 and pivotally attached thereto by means of a pin 54. A coil compression spring 55 positioned between the body lug 46 and the cross head 47 urges the latter, and consequently the needle valve, in a direction to normally close said valve. 100
- 105
- 110
- 115
- 120
- 125
- 130
- With the parts in the position shown in Figs. 1 and 2, it will be evident that when the trigger 22 is drawn back by finger action, the air-supply valve 36 will be directly opened as described above, and the needle valve 21 will remain closed until the yoke 51 moving with the trigger, has brought the end walls 56 of the slots 49 against the cross-head ends 48 which are fixed with respect to the needle valve. Upon continuing this trigger movement, the needle valve will be unseated, thereby delivering the material through the orifice 18 to be atomized by the action of the air. This relative timing of the valves is desired in order that the initial stream of air may blow away any foreign particles from the surface to be sprayed, and also to insure thorough atomization of the material the instant it issues from its respective nozzle. Upon release of the trig-

ger, the valve will obviously be closed by action of the springs 37 and 55. The timing of opening the material-delivery valve with respect to the air-supply valve may be varied as conditions may require, by axial adjustment of the needle valve in the sleeve 45. That is, by screwing said needle valve into said sleeve, the latter and consequently its cross head ends 48, will be advanced to the left viewing Fig. 1, by the pressure of the spring 55, thereby reducing the distance between said cross head ends and the end walls 56. To facilitate this adjustment, I have mounted a knurled disk 57 on the threaded end 44 of the needle valve stem, the opening in this disk being shaped to fit the flattened sides 58 of said stem, so that the disk and stem will revolve together, but the disk may slide lengthwise on the stem. By this means, the opening of the needle valve may be quickly and easily adjusted with relation to the opening of the air-supply valve.

It will be noted from the foregoing that the air and material regulating valves are located in a common plane below the barrel-like portion of the gun body. This enables a material reduction of the number of parts as compared with prior spray guns designed for similar work, and it follows that the cost of production is lowered not only because of the fewer number of parts involved, but also because of the alignment of the parts.

Another advantage of this arrangement is that the needle valve adjustment is conveniently accessible and all of the parts which for any reason might require removal for cleaning, repair and inspection, are easily removable. It will also be noted that all adjustments and the changing of moving parts and different sizes of nozzles may be made without disconnecting the material hose. By means of the screw 42, the air pressure may be instantly regulated to suit the particular work at hand. In the event that spraying effects other than flat sprays are desired, the present nozzle will be removed and another of appropriate construction substituted therefor.

A further advantage of my invention is that the operative parts are so relatively arranged and the body of the gun so shaped that the parts requiring adjustment are exposed and in a freely accessible location so that it is not necessary to remove or disassemble any of such operative parts in order to make the necessary adjustments. For example, the threaded member of the stuffing box for the needle valve at the place the latter passes rearwardly from the material supply passage 8 is accessible at all times for tightening the packing to prevent leakage. The several operative parts have been so organized and the body of the spray gun so shaped as to serve this purpose as one of the

objects of the invention. In this regard the needle valve adjustment is also preferably located between said stuffing box and the trigger so as to be conveniently accessible at all times.

It is believed that the foregoing conveys a clear understanding of the objects prefaced above, and while I have illustrated but a single working embodiment, it should be understood that changes might be made in details of construction without departing from the spirit and scope of the invention as expressed in the appended claims:

I claim:

1. In a spray gun, in combination, a body having an air and a material-supply passage, a material-delivery nozzle on said body in communication with the material-supply passage, and a flat spray air-delivery nozzle concentric with said material-delivery nozzle comprising a coupling part and an air-delivery part, the coupling part being threadedly connected to said body and bored to provide an air passage, the air-delivery part being mounted to swivel upon the coupling part and being wholly supported and retained on the latter by the swivel connection, the air delivery part being shaped to provide the outer wall of an air passage the inner wall of which is the material-delivery nozzle and which communicates with the first-mentioned air passage, and to provide an air discharge orifice concentric with the discharge orifice of the material-delivery nozzle, and to further provide opposed air-delivery orifices communicating with said air passage and terminating in angular relation for delivering converging streams of air intersecting the central material and air discharge.

2. A spray gun comprising, in combination, a body having a nozzle end and a handle end and provided with a material-supply passage in the nozzle end and an air-supply passage in the handle end in axial alignment, a material-delivery nozzle and an air-delivery nozzle in cooperative relation on said nozzle end, a needle valve for the material nozzle extending through and rearwardly beyond said material-supply passage, an air valve in the air-supply passage having a stem extending forwardly in axial alignment with the needle valve, a trigger pivoted on the body intermediate said needle valve and the air valve stem, a connection between said trigger and the air valve stem whereby the latter will be directly moved by rearward movement of the trigger, a lost-motion connection between said trigger and needle valve whereby the latter will be moved rearwardly by the trigger subsequently to the initial movement of the trigger, and adjustable means whereby the opening of the needle valve with respect to the air valve may be varied.

3. A spray gun comprising, in combination, a body having a nozzle end and a handle end and provided with a material-supply passage in the nozzle end and an air-supply passage in the handle end in axial alignment, a material-delivery nozzle and an air delivery nozzle in cooperative relation on said nozzle end, a needle valve for the material nozzle extending through and rearwardly beyond said material-supply passage, an air valve in the air-supply passage having a stem extending forwardly in axial alignment with the needle valve, a trigger pivoted on the body intermediate said needle valve and air valve stem, a connection between said trigger and air valve stem whereby the latter will be directly moved by rearward movement of the trigger, a yoke pivotally mounted to the trigger with its arms parallel with and straddling the rear end portion of the needle valve, a sleeve threaded on said rear end of the needle valve and having a crosshead the opposite ends of which have a lost-motion connection with the arms of said yoke, a coiled compression spring acting between said body and said sleeve to seat the needle valve, and means on the needle valve for turning it for purpose of adjustment. 70
4. A spray gun comprising, in combination, a body having a nozzle end and a handle end and provided with a material-supply passage in the nozzle end and an air-supply passage in the handle end in axial alignment, a material-delivery nozzle and an air-delivery nozzle in cooperative relation on said nozzle end, a needle valve for the material nozzle extending through and rearwardly beyond said material-supply passage, an air valve in the air-supply passage having a stem extending forwardly in axial alignment with the needle valve, a trigger pivoted on the body intermediate said needle valve and air valve stem, a connection between said trigger and air valve stem whereby the latter will be directly moved by rearward movement of the trigger, a connection between the trigger and needle valve including a part threaded on the rear end of the needle valve, and means for turning the needle valve in said part for effecting relative adjustment between the opening of the air and needle valves. 80
5. A spray gun comprising, in combination, a body having a handle and a head joined by a barrel portion, the head having a material-supply passage beneath said barrel portion, the handle having an air-supply passage in axial alignment with said material-supply passage, a material-delivery nozzle on the head having a valve stem extending through and rearwardly beyond the material-supply passage, a packing between said stem and the head at the rear end of said passage therein, a part threadedly engaged with the head for compressing said packing around the valve stem, the body being shaped to expose said part so that it is accessible for adjustment without disturbing any of the operative parts, an air-delivery nozzle on the head in cooperative relation with the material nozzle, an air passage through the barrel portion connecting the air passage in the handle with the air nozzle, a valve normally closing the air-supply passage, and a trigger pivoted on the barrel portion and connected with said needle valve and air valve for operating them. 85
6. A spray gun comprising, in combination, a body, a nozzle structure on one end of the body and a handle on the opposite end, the nozzle structure including a needle valve and a stuffing box through which the stem of the needle valve passes and extends rearwardly toward the handle, a trigger mounted on the gun body intermediate the nozzle structure and handle and connected with the needle valve for unseating it, said body intermediate the nozzle structure and handle being shaped to expose said stuffing box so that it is accessible for tightening its packing around said valve stem without disassembling any of the operative parts. 90
7. A spray gun comprising, in combination, a body, a nozzle structure on one end of the body and a handle on the opposite end, said nozzle structure including a material delivery nozzle and a needle valve therefor, the stem of said needle valve extending rearwardly toward the handle, a trigger mounted on the body intermediate said nozzle structure and handle, and means whereby the needle valve will be unseated by the operation of the trigger, including a threaded connection with said valve stem and a part located between the trigger and said nozzle structure adapted for turning one of the threaded parts for effecting adjustment of the needle valve with respect to the trigger. 100
8. A spray gun comprising, a body, a nozzle structure and a handle on opposite ends of the body, a trigger mounted on the body intermediate said nozzle structure extending rearwardly toward the handle, a yoke pivoted to the body and having a crosshead with which the needle valve is connected, a compression spring interposed between the body and said yoke under a tension tending to seat the needle valve, a threaded connection between the needle valve and yoke, and a part slidably lengthwise on the needle valve and connected to rotate therewith for adjusting the needle valve in its threaded connection with the yoke. 110
9. A spray gun of the character described, including a body having a nozzle structure and a handle at opposite ends and a trigger therebetween, the nozzle structure including a material delivery nozzle and an air nozzle and having a needle valve for the ma- 125

- terial delivery nozzle extending rearwardly toward the trigger, an air supply valve in the handle end of the gun co-axial with the needle valve and having communication with the air nozzle and adapted to be unseated for delivering air thereto, said air valve extending forwardly toward the trigger, means whereby both the needle valve and air valve will be unseated by operation of the trigger, and a stuffing box for the needle valve located between the trigger and the nozzle structure, said body being so shaped that the stuffing box is accessible for tightening the packing around the needle valve without disturbing any of the operative parts of the spray gun.
10. A spray gun comprising, in combination, a barrel portion, a nozzle structure and a handle joined and held in relation by said barrel portion, a trigger pivoted on said body portion, a needle valve for said nozzle structure extending rearwardly therefrom in a plane parallel with and spaced from said barrel portion, a lug on said barrel portion extending across the plane of said needle valve, a compression spring bearing at one end against said lug and at its opposite end against the needle valve for seating the latter, and a connection between the trigger and needle valve for unseating the latter against pressure of said spring.
11. A spray gun comprising in combination, a body portion, a nozzle structure and a handle joined and held in fixed relative relation by said body portion, a trigger having spaced arms which straddle said body portion and are pivoted thereto, a needle valve for said nozzle structure in a plane parallel with and spaced from said intermediate body portion and disposed between the spaced arms of the trigger, a cross-head on the needle valve, a compression spring on the needle valve operative between said body portion and said cross-head for seating said needle valve, and a connection between each trigger arm and the adjacent end of the cross-head for unseating the needle valve against the spring pressure.
12. A spray gun as set forth in claim 11, including an air valve in the handle end of the gun coaxial with the needle valve and adapted to be unseated by operation of the trigger, said body portion having an air passage extending longitudinally therethrough and providing communication between said air valve and the nozzle structure for delivering air to the latter.
13. A spray gun comprising, in combination, a body carrying a nozzle supporting head at one end and a handle at the opposite end, said head having a material supply passage and said body having an air supply passage, a nozzle structure on said head in communication with said material and air supply passages, a needle valve for the nozzle passing through the material supply passage and beyond the same toward the handle, a trigger-mounted on the body intermediate said head and handle and connected with said needle valve for unseating it, means preventing leakage of material from said material supply passage around or past the needle valve including a packing and a stuffing box therefor having a threaded member adapted to be tightened to compress the packing about the needle valve, said body being shaped intermediate said head and handle to expose said threaded member so that it is accessible at will for compressing said packing without disturbing any of the operative parts of the spray gun.

SWAN F. ANDERSON.

terial delivery nozzle extending rearwardly toward the trigger, an air supply valve in the handle end of the gun co-axial with the needle valve and having communication 5 with the air nozzle and adapted to be unseated for delivering air thereto, said air valve extending forwardly toward the trigger, means whereby both the needle valve and air valve will be unseated by operation 10 of the trigger, and a stuffing box for the needle valve located between the trigger and the nozzle structure, said body being so shaped that the stuffing box is accessible for tightening the packing around the needle 15 valve without disturbing any of the operative parts of the spray gun.

10. A spray gun comprising, in combination, a barrel portion, a nozzle structure and a handle joined and held in relation by said 20 barrel portion, a trigger pivoted on said body portion, a needle valve for said nozzle structure extending rearwardly therefrom in a plane parallel with and spaced from said barrel portion, a lug on said barrel portion 25 extending across the plane of said needle valve, a compression spring bearing at one end against said lug and at its opposite end against the needle valve for seating the latter, and a connection between the 30 trigger and needle valve for unseating the latter against pressure of said spring.

11. A spray gun comprising in combination, a body portion, a nozzle structure and a handle joined and held in fixed relative 35 relation by said body portion, a trigger having spaced arms which straddle said body portion and are pivoted thereto, a needle valve for said nozzle structure in a plane parallel with and spaced from said intermediate body portion and disposed between the spaced arms of the trigger, a cross-head 40 on the needle valve, a compression spring

on the needle valve operative between said body portion and said cross-head for seating said needle valve, and a connection between each trigger arm and the adjacent end 45 of the cross-head for unseating the needle valve against the spring pressure.

12. A spray gun as set forth in claim 11, including an air valve in the handle end 50 of the gun coaxial with the needle valve and adapted to be unseated by operation of the trigger, said body portion having an air passage extending longitudinally therethrough 55 and providing communication between said air valve and the nozzle structure for delivering air to the latter.

13. A spray gun comprising, in combination, a body carrying a nozzle supporting head at one end and a handle at the opposite end, said head having a material supply passage and said body having an air supply passage, a nozzle structure on said head in communication with said material and air supply passages, a needle valve for the nozzle passing through the material supply passage and beyond the same toward the handle, a trigger-mounted on the body intermediate said head and handle and connected with said needle valve for unseating 70 it, means preventing leakage of material from said material supply passage around or past the needle valve including a packing and a stuffing box therefor having a threaded member adapted to be tightened to 75 compress the packing about the needle valve, said body being shaped intermediate said head and handle to expose said threaded member so that it is accessible at will for compressing said packing without disturbing any of the operative parts of the spray gun.

SWAN F. ANDERSON.

Certificate of Correction.

It is hereby certified that in Letters Patent No. 1,583,220, granted May 4, 1926, upon the application of Swan F. Anderson, of Rockford, Illinois, for an improvement in "Spray Guns," an error appears in the printed specification requiring correction as follows: Page 5, line 19, claim 10, before the word "relation" insert the word *operative*; and that the said Letters Patent should be read with this correction therein that the same may conform to the record of the case in the Patent Office.

Signed and sealed this 8th day of June, A. D. 1926.
